UNITED STATES PATENT OFFICE.

IDA M. ROUSE, OF KANSAS CITY, MISSOURI.

DRESS OR SKIRT GAGE.

No. 809,464.

Specification of Letters Patent.

Patented Jan. 9, 1906.

Application filed August 1, 1905. Serial No. 272,253.

To all whom it may concern:

Be it known that I, Ida M. Rouse, a citizen of the United States, residing at Kansas City, in the county of Jackson and State of Missouri, have invented new and useful Improvements in Dress or Skirt Gages, of which the following is a specification.

My invention relates to improvements in skirt-gages.

- 10 The object of my invention is to provide a gage by which a skirt or dress may be fitted upon the wearer so that the lower edge will hang at a uniform distance at all points from the floor.
- 15 My invention provides a device having a vertical transversely - graduated standard supported on a base adapted to be placed upon the floor, a member having means for engaging and holding the folded lower edge of the
- 20 dress or skirt being vertically adjustable upon the standard and releasable means being provided for locking the skirt-support in any position upon the standard to which it may be adjusted.
- 25 Other novel features of my invention are hereinafter fully described and claimed.

In the accompanying drawings, illustrating my invention, Figure 1 is a side elevation view of the skirt-gage, showing a part of the 30 folded lower edge of a skirt or dress mounted thereon. Fig. 2 is a top view. Fig. 3 is a perspective view of the skirt - supporting member.

Similar characters of reference denote similar parts.

- 35 1 denotes a horizontal base, preferably provided with feet 2, adapted to rest upon the floor. A vertical standard 3 has its lower end secured rigidly to the base 1, said standard being provided with a series of transverse 40 graduations 4. Vertically slideable upon the standard 3 is a skirt or dress support comprising, preferably, a metal U-shaped body, the horizontal parallel arms 5 and 6, respectively, of which are disposed one above the other, said arms having each a vertical hole 7, in which the standard 3 is slideable. The 45 vertical portion 8 of the body between the arms 5 and 6 is provided with a transverse screw-threaded hole, in which is fitted a horizontal thumb-screw 9, the inner end of which is adapted to bear against the adjacent edge of the standard 3 for securing the skirt thereto in any position in which it may be adjusted 50 thereon. The end of the arm 5 distant

from the portion 8 is provided with means for supporting a skirt or dress (denoted by 10) and comprising, preferably, an upwardly-extending arm 11, preferably resilient and between which and the standard 3 the skirt or dress 10 is adapted to be held.

In operating the invention the skirt-support is vertically adjusted upon the standard 3 to a position in which the upper side of the arm 5 will register with the graduation 4 on the standard 3, representing the height it is desired to have the lower edge of the skirt or dress from the floor. The base 1 is then moved upon the floor to a position adjacent the person to whom the dress or skirt is being fitted, after which the lower edge of the skirt or dress is folded, as shown in Fig. 1, and inserted between the arm 11 and the standard 3, the material being folded so that the lower edge of the folded portion rests upon the upper side of the arm 5. The folded portion of the skirt or dress 10 thus being held by the arm 11 and standard 3, the hands of the operator are free to secure the folded portion of the skirt or dress by pinning or stitching, after which the base 1 is moved a convenient distance around the person wearing the dress or skirt, and the operation just described is repeated. The base 1 is consecutively moved from point to point around the person, the operations described being repeated at each point until the entire lower edge of the skirt has been folded in the proper manner and secured in the folded form. By adjusting the skirt-support upon the standard to any desirable height the dress or skirt may be made to hang at any desired distance from the floor, the distance all around the skirt or dress being uniform regardless of irregularities of the figure of the person to whom the dress or skirt is being fitted. The arm 11 is preferably resilient to accommodate the device to material of different thicknesses.

My invention may be subjected to different modifications without departing from its spirit.

Having thus described my invention, what I claim, and desire to secure by Letters Patent, is—

1. In a skirt-gage, the combination with a base, of a vertical standard mounted thereon, a skirt-support comprising a U-shaped body having the two parallel arms disposed horizontally one above the other, said arms having perforations respectively through which

the standard extends, the body being vertically slidable upon the standard, and one of the arms of the body being provided with means for engaging and holding the lower edge of a part of a skirt.

2. In a skirt-gage, the combination with a base, of a vertical graduated standard mounted thereon, a skirt-support comprising a **U**-shaped body having the two parallel arms disposed horizontally one above the other, the arms being vertically slidable upon the standard, one arm being disposed so as to indicate the graduations on the standard and provided with means for engaging and holding the lower edge of a part of a skirt, and releasable means for securing the said body to the standard.

3. In a skirt-gage, the combination with a base, of a vertical standard mounted thereon, a skirt-support comprising a **U**-shaped body the parallel arms of which are disposed horizontally one above the other and slidable vertically on the standard, one arm having means for engaging and holding the lower edge of a part of a skirt, and the vertical part of the **U**-shaped body having a transverse screw-threaded hole, and a securing-screw mounted in said threaded hole in the body and adapted to bear against the standard.

4. In a skirt-gage, the combination with a base, of a vertical standard mounted thereon and having a series of transverse graduations, a skirt-support comprising a **U**-shaped body the parallel arms of which are disposed horizontally one above the other and slidable vertically each upon the standard, one arm having means for engaging and holding the lower edge of a part of a skirt and disposed so as to indicate the graduations on the standard, the vertical portion of the **U**-shaped body having a transverse screw-threaded hole, and a securing-screw mounted in said threaded hole and adapted to bear against said standard.

5. In a skirt-gage, the combination with a base, of a vertical standard mounted thereon, a skirt-support comprising a **U**-shaped body the parallel arms of which are disposed horizontally one above the other and slidably vertically upon the standard, one arm having thereon an upwardly-extending arm between which and the standard the skirt is adapted to be held, the vertical portion of the body connecting the horizontal arms having a transverse screw-threaded hole, and a securing-screw mounted in said hole and adapted to bear against the standard.

ing-screw mounted in said hole and adapted to bear against the standard.

6. In a skirt-gage, the combination with a base, of a vertical standard mounted thereon and having a series of transverse graduations, a skirt-support comprising a **U**-shaped body the parallel arms of which are disposed horizontally one above the other and slidable vertically upon the standard, one of said arms having an upwardly-extending arm between which and the standard the lower edge of a skirt is adapted to be held, the arm having the upwardly-extending arm being disposed so as to indicate the graduations, the vertical portion of the **U**-shaped body connecting the parallel arms having a transverse threaded hole, and a securing-screw mounted in said hole and adapted to bear against the standard.

7. In a skirt-gage, the combination with a base, of a vertical standard mounted thereon, a skirt-support comprising a **U**-shaped body having the parallel arms disposed horizontally one above the other and slidable vertically upon the standard, one arm having an upwardly-extending resilient arm between which and the standard the lower edge of a skirt is adapted to be held, the vertical portion of the body connecting the parallel arms having a transverse screw-threaded hole, and a securing-screw fitted in said hole and adapted to bear against said standard.

8. In a skirt-gage, the combination with a base, of a vertical standard mounted thereon and having a series of transverse graduations, a skirt-support comprising a **U**-shaped body the parallel arms of which are disposed horizontally one above the other and slidable vertically on said standard, one arm being disposed so as to indicate the graduations and having extending upwardly therefrom a resilient arm between which and the standard the lower edge of a skirt is adapted to be held, the vertical portion of the body connecting the parallel arms having a transverse screw-threaded hole, and a securing-screw mounted in said hole and adapted to bear against the standard.

In testimony whereof I affix my signature in presence of two subscribing witnesses.

IDA M. ROUSE.
